UNITED STATES PATENT OFFICE.

FÉLIX EMILE VALOIS, OF BRIDGEPORT, CONNECTICUT, ASSIGNOR TO HAMEL SHOE MACHINERY COMPANY, A CORPORATION OF MASSACHUSETTS.

SHOE-SEWING MACHINE.

Application filed July 14, 1919. Serial No. 310,718.

To all whom it may concern:

- Be it known that I, FÉLIX E. VALOIS, a citizen of the United States, residing at Bridgeport, in the county of Fairfield and State of Connecticut, have invented certain new and useful Improvements in Shoe-Sewing Machines, of which the following is a specification, reference being had therein to the accompanying drawings.
- 10 This invention relates to sewing machines and more particularly to chain stitch shoe sewing machines of that type which employ a curved, hook needle and a waxed thread and are used for sewing the inseams of welt shoes, or for sewing the sole to the upper of turn shoes.
- 15 The needles employed in machines of this type are usually provided with a barb or hook upon one side having leading therefrom a spiral groove passing around the back of the needle and terminating near the point thereof at the forward side. In the operation of such machines the needle is thrust forwardly through the material of 20 the shoe and the looper thereupon travels around the needle laying the thread in its barb. The needle now retracts drawing the loop of thread through the work the needle usually dwelling more or less in its rearmost 25 position while the work feed mechanism traverses the shoe the space of a stitch length to the left. As the shoe thus moves, one side of the thread loop extending from the needle hook to the shoe is dragged against the right 30 side of the needle and across the front thereof resting in the spiral groove aforementioned. This action produces a crossing or twisting of the loop rendering it difficult to disengage the loop from the needle barb.
- 35 Upon the further actuation of the machine the needle advances toward the material and as the point of the needle penetrates the work the loop is forced out of the barb and slides onto the shank of the needle, the loop being stretched lengthwise of the work from the last perforation formed therein by the needle. When the barb of the needle has passed through the work it is in position for receiving a new loop from the looper, 40 and in retracting to draw the new loop through the loop held upon its shank. This

cycle of operations may be repeated indefinitely to form a chain stitch seam.

During the above cycle of operations it will be noted that the needle either extends 55 through the material with the loop of thread around its shank, or is retracted from the work with the thread held firmly in its barb. It is obvious that were the machine stopped with the needle in the work it 60 would be difficult to remove the work from the machine, the position of certain auxiliary parts of the mechanism also interfering with such action and rendering it practically impossible of performance. It is therefore 65 necessary to stop the machine at the completion of the operation with the needle out of the work in retracted position, but when in such position the loop is firmly held in the barb as above described, the wax upon 70 the thread adding to the difficulty of separating the loop from the needle. In the operation of this type of machine when unprovided with a stop motion, the operator is obliged to take hold of the fly wheel with 75 his hand and by reversely rotating the shaft and by manipulation of the shoe cause the needle to advance slightly and the loop to be disengaged from the barb, whereupon he cuts the side of the loop leading to the looper 80 and removes the shoe from the machine.

In machines provided with a stop motion it is desirable to provide for automatically freeing the loop from the needle barb at the completion of the operation, first to save 85 the time and strength of the operator otherwise consumed in reversing the shaft, and second because in the use of many stop mechanisms the shaft is so locked in stopping as to render such hand reversal of the 90 shaft impossible.

Many attempts have been made to attain the desired result, as by the provision of automatically acting means for reversing the shaft, means for preventing the laying of 95 the thread in the needle barb just prior to the last retraction of the needle or by giving the needle a slight advancing movement after its final retraction whereby to loosen the barb from the loop.

Some of the above devices have proven fairly satisfactory in commercial use but in

most cases involve the use of complicated mechanism adding materially to the cost and upkeep of the machine.

The present invention seeks to attain the desired end by the use of relatively simple devices readily applicable to a machine provided with a stop motion and by the use of which the work is released from the needle with certainty and substantially no loss of time on the part of the operator. To accomplish this result the machine is provided with an attachment which frees the thread forming the last needle loop from the needle hook while the latter is maintained in its rearmost retracted position, such action taking place substantially simultaneously with, or slightly after the final movement of the drive shaft, a brake being preferably employed for bringing such shaft to rest. While such disengagement of the thread from the barb while the needle is in the above position may be accomplished by various means, that herein disclosed consists in the provision of a device for severing one side of the loop. While such a severing device may be mounted and actuated in many ways it is preferred as shown herein to fix a cutter upon the needle guide and to impart to the latter an abnormal movement at the end of the last stitch cycle whereby to cut that side of the highly tensioned loop which lies upon the forward surface of the needle adjacent the barb. Such movement is transmitted to the needle guide by connections from the brake operating mechanism whereby the cutter is caused to operate substantially at the instant the cam shaft comes to rest.

As the thread leading from the looper to the needle is at this time under a certain amount of tension due to the action of the auxiliary take-up, the end of the thread upon cutting of the loop would ordinarily be whipped back through the looper eye which action is to be avoided as it is desirable that the thread extend from the looper eye to permit the operator to draw out a sufficient quantity to enable the machine to function properly in starting.

The present invention provides means for rendering the auxiliary take-up inoperative at the instant of cutting the loop and during the stoppage of the machine, such means comprising a member actuated by connections from the brake applying mechanism and acting to elevate the auxiliary take-up roll in opposition to its controlling spring.

While the mechanism herein disclosed is a preferred form of the invention it is regarded as within its scope to provide any or all other means for causing separation or removal of the thread from the needle barb while the needle is positioned in its rearmost retracted position.

Other objects and advantages of the pres-

ent invention, together with improved details of construction and advantageous combinations of parts will be more fully disclosed in the following specification and particularly pointed out in the claims, reference being had to the annexed drawings in which,

Fig. 1 is a side elevation of so much of a machine head as is necessary to show the application of the present invention thereto, certain parts being omitted or broken away for clearness of illustration;

Fig. 2 is a front elevation of the parts shown in Fig. 1;

Fig. 3 is a diagrammatic illustration showing the needle and needle guide in normal forward position;

Fig. 4 is a diagrammatic view showing the needle in rearward position and the needle guide in abnormal forward position;

Figs. 5 and 6 are side and end elevations, respectively, illustrating a form of stop mechanism which may be employed in carrying out the present invention.

The numeral 1 indicates the machine head having rising therefrom posts 2 and 3 in which are provided bearings for a main shaft 4, this shaft being adapted for receiving a series of cam discs of the usual type, such as are employed in machines of this class for operating the various sewing instrumentalities. One of such cam discs is indicated at 5, such disc being provided upon its right hand face with a needle actuating groove 6 and upon its left hand face with a needle operating groove 7.

Cooperating with the groove 6 is a roll 8 carried upon one arm of the bell crank lever 9 pivoted upon a stud 10 secured in the machine frame. The forward arm of the bell crank lever is connected as by means of link 11 with an oscillatory needle sector 12 mounted to swing about a fixed pivot 13, said needle sector having fixed therein a grooved needle 14 having a side hook as shown at 15, the parts as hereinbefore described being of common and well known construction.

16 is a rock shaft arranged substantially parallel to the main shaft 4 and mounted to turn in a fixed bearing 17, said shaft having fixed upon its left hand extremity an arm 18 which extends upwardly and to the rear. Extending from the left hand face of said arm is a lug 19 having a threaded opening for the reception of an adjustable stop screw 20 which may if desired be provided with a lock nut 21. Upon the shaft 16 adjacent the arm 18 and to the left thereof is an arm 22, said arm being connected to the arm 18 by means of a coil spring 23 whose opposite extremities engage pins 24, 25 fixed in the respective arms. Upon the extremity of the arm 22 is mounted a roll 26 engaging the cam groove 7. Fixed

to the right hand extremity of the rock shaft 16 is an arm 27, the lower extremity of which is connected by means of a link 28 with an arm 29 extending upwardly from the needle guide sector pivotally supported upon the pin 13, said needle guide sector having projecting therefrom a needle guide 30 provided with an opening for the passage of the needle. 31 is a cutter blade having a forwardly projecting edge and secured to the guide by means of a screw 32 or in any other suitable manner.

33 indicates the usual channel guide and 34 the looper, while 35 is the take-up lever provided at its forward extremity with a roll 36 over which the thread passes and having a connection 37 by means of which the lever is actuated from a suitable cam, not shown, carried upon the shaft 4, all in the usual and known manner. 38 is an auxiliary take-up lever pivoted to swing about a stud 39 forming the support for the lever 35, said lever 38 being provided at its forward extremity with a thread guiding roll 40, a thread guiding roll 41 also being provided concentric with the pivot 39. The spring 42 normally tends to move the auxiliary take-up lever 38 in a downward and rearward direction, whereby the thread T, which passes from the supply over the roll 41, under the roll 40, and over the roll 36, is normally placed under tension, the thread from the roll 36 passing downwardly and through the eye of the looper 34 to the work.

At some suitable point on the shaft 4, herein shown as at the right hand extremity thereof, is a brake disc 43. Pivoted at the point 44 upon the head is a curved brake lever 45 provided with a brake shoe 46 adapted to partially encircle the disc 43 and to be brought into contact therewith to stop its rotation. 47 is a rock shaft mounted in bearings 48, 49 provided in the machine head, said shaft lying substantially parallel to the shaft 4 and having upon its left hand extremity an arm 50 to which is connected a rod 51 which may be actuated through any suitable stop mechanism, such as is commonly employed in the art for stopping the cam shaft at a predetermined point in its rotation, such stop motion acting to turn the arm 50 in a counter-clockwise direction as shown in Fig. 1 in stopping the machine, thus rocking the shaft 47 rearwardly.

Such a stop motion is illustrated in Figs. 5 and 6, wherein 4 is the main shaft of the machine having a bearing in the post 2, said post having upon its left hand face a fixed wedge member 100 provided with a surface 101 for engagement with a vertically adjustable cooperating wedge member 102. The wedge member 102 is provided with a vertically elongated opening for the passage of shaft 4, and bears at its left hand face

against one element of an anti-friction device comprising a pair of rings 103, 104 having interposed therebetween ball bearings 105. 106 indicates a grooved pulley mounted to turn freely upon the shaft 4. A cam member 107 is interposed between the pulley 106 and the ring 104, and is slidably mounted upon the shaft but is locked by usual or suitable means from turning thereon, as by a spline-and-groove connection 4'. 108 is a fly wheel fast upon the outer extremity of the shaft 4, and provided at 109 with a hub arranged for engagement with a friction washer 110 carried upon the left hand face of the pulley 106. 111 is a yoke member having pivotal engagement as by means of pins 112 with diametrically opposite points of the wedge member 102, the lower extremity of said yoke being pivoted at 113 to the top of a treadle rod 114, said rod passing up through an opening 115 in the head and being adapted for connection to an operating treadle of ordinary form.

116 is a bracket fast to the rod 114 below the connection of the latter to the yoke member, and 117 is a coil compression spring surrounding the rod and having its opposite ends bearing against the upper surface 118 of the head member and the lower surface of the bracket 116. Bracket 116 is bifurcated at its extremity and provides bearings for a cam engaging roll 119, said roll being adapted to engage the surface of the cam 107. The latter cam is substantially circular throughout the greater portion of its extent, but is cut away at 120 to form a depression into which the roll 119 may ride at times. 121 is an ear extending outwardly from the wedge member 102 and having pivoted thereto a link 122 which in turn is pivoted at the point 123 to the lower extremity of the rod 51 which actuates the shaft 47 connected to the brake. In the operative position of the parts with the machine running the wedge member 102 is in the position shown in Fig. 5 with the spring 117 under compression and the friction surface 110 in contact with the hub 109 of the drive pulley, whereby the shaft is placed in operation. The roll 119 at this time occupies a position adjacent the circular portion of cam 107, and the arm 50 of the brake-operating shaft 47 has been pulled down into the position shown in Fig. 6 whereby to disengage the brake from the brake wheel. When it is desired to stop the machine, the operator removes his foot from the treadle thus permitting the spring 117 to act. The spring is unable, however, to lift the rod 114 until such time as the roll 119 comes opposite the depressed portion 120 of cam 107, such depressed portion of the cam being so positioned relative to the stitch-forming instrumentalities of the machine that the rod 114 is only per-

mitted to rise when the needle and other stitch-forming instrumentalities are in position for removal of the work. Upon the movement of roll 119 into the depression 120 5 wedge 102 is permitted to rise under action of spring 117 thus releasing the fly wheel from driving connection with pulley 106. At the same time rod 51 is moved upwardly 10 thus turning arm 50 in a counter-clockwise direction and through shaft 47 actuating the 15 brake to stop the machine.

While the above simple form of stop mechanism is disclosed herein as one well adapted for use in connection with the 20 mechanism otherwise disclosed herein, no claims are made thereto in this application, it being understood that any equivalent stop motion device adapted to stop the main shaft at a predetermined position could well 25 be substituted therefor without departing from the scope of the present invention.

Near its right hand extremity the shaft 47 has fixed thereto an arm 52 connected by 30 means of a link 53 with a stud 54 fixed to the brake lever 45, whereby rocking of the shaft 47 as above described serves to press the brake shoe into contact with the disc 43. 35 55 is an arm also fixed to the shaft 47, said arm lying in the plane of the arm 18 carried upon the rock shaft 16 and having its extremity lying to the rear of and below the rear extremity of the arm 18. By this construction upon rearward rocking of the shaft 47 the arm 55 will be brought into contact with the arm 18, whereby the latter will be rocked in a clockwise direction thus rocking shaft 16 forwardly.

56 is another arm fast to the shaft 47, the lower end of which is connected by means of a 40 pin 57 with the rear extremity of a link member 58. The link member 58 at its forward portion is provided with an off-set arm 59 having a surface 60 adapted to slidably rest upon a guide surface 61 formed upon a bracket 62 fixed to a suitable portion of the machine frame. The link member 58 at its forward portion is also provided with a downwardly 45 extending arm 63 having a substantially vertical surface 64 normally lying just to the rear of a pin 65 outstanding from the left hand face of the auxiliary take-up lever 38. Upon the rearward rocking of the shaft 47 as above described when the machine 50 stops the lower end of the arm 56 will be moved forwardly, thus causing a forward 55 sliding movement of the link 58 along its guide 61 whereby the surface 64 of the arm 63 is brought into contact with the pin 65, 60 thus swinging the auxiliary take-up about its pivot 39 in opposition to its actuating spring, thereby relieving the thread T of any tension tending to draw the same backwardly through the eye of the looper.

65 In the normal operation of the machine

the needle, looper, needle guide, take-up, and auxiliary take-up, function in the usual manner to form a succession of stitches, each revolution of the cam shaft 4 completing a cycle of stitch forming operations. During 70 the normal operation the needle guide 30 moves downwardly following the forward movement of the needle in order to support the same during its penetration into the work, the guide, however, always retracting prior to the retracting movement of the needle and in the rearmost position of the needle occupying a position relative thereto, such as indicated in Fig. 1, wherein the cutting blade 32 is out of contact with the 75 thread forming the needle loop and which lies in the barb of the needle.

When it is desired to stop the machine, the operator removes his foot from the treadle in the usual manner permitting the stop mechanism to separate the driving clutch elements at a predetermined point in the revolution, such point being that at which the needle occupies its rearmost position. When the stop motion mechanism 80 operates to separate the clutch elements, the rod 51 is automatically raised by means of the spring 117 under the controlling action of the cam 107, rocking the shaft 47 to the rear as previously described to apply the 85 brake. Such movement of the shaft through the action of the arm 55 causes an abnormal forward movement of the needle guide 30 and as the needle is stationary at this time the cutting blade 31 is brought into contact with one side of the thread forming the last 90 needle loop and which is held in the barb of the needle. This thread is held under high tension due to the retraction of the needle and is thus very readily severed by contact 95 of the cutting blade therewith.

Such action of the needle guide is permitted while the cam shaft remains stationary by reason of the resilient connection consisting of the spring 23 by which the arms 110 22 and 18 are united, this connection permitting the arm 18 to be moved in a clockwise direction independently of the arm 22, the latter, however, when actuated by the cam 7 operating positively through the stop 115 20 to give the needle guide its forward operative motion. Substantially simultaneously with the action of the cutting blade the auxiliary take-up is rendered inoperative by the movement of the link 58, thus preventing the thread, after being severed, from being whipped upwardly thereby through the looper eye by reason of the tension normally imparted thereto by said auxiliary take-up.

120 After the stoppage of the machine and the cutting of the thread, the operator may freely remove the work from the machine as the needle at this time is out of the work, and as the end of the thread remains pro- 125

- jecting from the looper eye the operator may pull off a sufficient quantity from the supply to provide for proper starting of the machine upon the next succeeding operation.
- 5 By the above arrangement of parts it will be readily seen that the present invention provides in a simple and effective manner for permitting the ready withdrawal of the work from the machine in stopping, and
- 10 without the necessity for changing the usual motions of the principal parts of the machine, such as the needle, looper and the operating connections therefor, and without the necessity of reversing the movement of
- 15 the cam shaft in stopping. As herein shown the severing of the thread has been described as accomplished by an abnormal movement of the needle guide but it is clear that a movement of the needle rearwardly
- 20 through a stationarily held guide would produce a similar result.
- While in the present disclosure a cutter blade connected to the needle guide has been shown it is contemplated as within the scope
- 25 of the present invention to provide a cutting device carried by some other reciprocable part of the machine and operating in proper time with the stop mechanism to produce the desired result. It is further-
- 30 more contemplated that means other than a cutting blade may be employed for freeing the thread from the needle hook insofar as such means are included within the scope of the appended claims.
- 35 Having thus described the invention in a preferred embodiment thereof, together with the mode of operation of the same what I claim and desire to secure by Letters Patent of the United States is,—
- 40 1. In a machine of the class described, in combination, sewing instrumentalities including a hooked needle and looper, mechanism for imparting to said needle a thread receiving and a thread drawing movement,
- 45 and means for severing the thread adjacent the needle hook, said means including devices for insuring the operation of the thread-severing means substantially at the end of a thread drawing movement of the
- 50 needle.
2. In a shoe sewing machine having stitch-forming instrumentalities including a curved, hooked needle and a looper, in combination, mechanism for imparting to said needle a forward movement to receive the thread in its hook and a rearward thread-drawing movement, and operator controlled means ineffective during the normal operation of the machine and movable relatively
- 55 to said needle for engaging the thread and for freeing it from said needle in the extreme retracted position of the latter.
3. A chain-stitch shoe sewing machine having, in combination, stitch-forming devices including a curved, hooked needle and
- 60
- a looper, a main-shaft from which said devices are operated, controlling mechanism to cause the needle to come to rest at the completion of a normal stitch-drawing movement, and means ineffective during the normal operation of the machine and actuated by said controlling mechanism for engaging the last loop of thread to free it from the hook of the needle in the rest-position of the needle.
- 70
4. In a machine of the class described, in combination, stitch forming devices including a hooked needle and a looper, mechanism for imparting to said needle a movement to position the same for receiving thread in its hook and a rearward movement for drawing the thread to form a stitch, and means ineffective during the normal operation of the machine and actuated independently of the needle actuating mechanism but timed by connection therewith for action in a predetermined stage of a stitch-forming cycle for freeing the thread from the stitch forming device substantially at the end of a rearward movement of the needle.
- 75
5. In a shoe sewing machine having stitch forming devices including a curved hooked needle and a looper, in combination, mechanism for moving the needle into position for receiving thread in its hook and for retracting it to draw a stitch, means for stopping the machine with the needle retracted and out of engagement with the work, and devices including an element ineffective during the normal operation of the machine associated with said stopping means and actuated independently of but timed for action in a predetermined stage of a stitch-forming cycle of the needle actuating mechanism for freeing the thread from the hook of the retracted needle.
- 80
6. In a chain stitch shoe sewing machine having stitch forming instrumentalities including a curved hooked needle and a looper, in combination, means for actuating said instrumentalities cycle after cycle to form a succession of stitches and normally ineffective mechanism automatically rendered effective upon stopping of the machine to during a forward cycle of operation engage the thread of the last needle loop to free it from the needle hook while the latter is in substantially its rearmost retracted position.
- 85
7. A machine of the class described having, in combination, stitch forming devices including a hooked needle and looper, means for actuating said devices to form a succession of stitches, and means acting automatically upon stopping the machine to sever the thread to free the same from the needle hook.
- 90
8. In a shoe sewing machine employing a hooked needle and a looper, in combination, a reciprocating part, a cutting blade mounted thereon, operating mechanism for normally actuating said needle, looper and
- 95
- 100
- 105

- 125
- 130

reciprocator part during the formation of a seam, and means acting automatically upon stopping the machine for giving said part an abnormal reciprocation whereby to bring said blade into cutting relation of the last needle loop.

9. In combination in a shoe sewing machine having a curved, hooked needle, and a needle guide, means for actuating said parts cycle after cycle in the formation of successive stitches, a thread severing device mounted upon said needle guide, and mechanism acting automatically upon stopping the machine to impart an abnormal movement to said needle guide whereby to bring said device into severing relation to the thread of the last needle loop.

10. In a shoe sewing machine, the combination with a needle of an oscillatory needle guide, a thread-cutter mounted thereon means for imparting to said guide normal and abnormal movements, said means comprising a lever, a rotary cam for imparting to said lever a normal oscillation during the stitching operation, and a rockable member for imparting to said lever an abnormal movement in stopping the machine whereby to bring said cutter into severing relation with the thread of the last needle-loop.

11. A chain stitch shoe sewing machine having, in combination, operating instrumentalities including a looper, a curved hooked needle, an oscillatory guide for the needle, a cutting blade mounted thereon mechanism for normally actuating said instrumentalities cycle after cycle in the formation of stitches, devices for bringing said needle to rest in a predetermined position out of the work, and means associated with said device for imparting an abnormal movement to said needle guide during the last cycle of operation whereby to bring said cutting blade into severing relation to the thread held in the needle hook.

12. In a chain stitch shoe sewing machine, in combination, a curved hooked needle, an oscillatory needle guide, a thread cutting blade fixed to said guide, means for imparting normal movements to said needle and guide during the formation of stitches and means actuatable at the will of the operator for imparting an abnormal forward motion to said guide when the needle is in retracted position whereby to bring the edge of said blade into cutting relation to the thread held by the needle hook.

13. The combination in a shoe sewing machine of a curved needle, an oscillatory needle guide, a thread-cutter mounted thereon means for actuating said guide comprising a rock shaft having an arm operatively connected to said guide and a second arm provided with an adjustable stop screw, a third arm loosely pivoted upon said shaft adjacent said second arm, a spring connect-

ing said arms whereby normally to maintain said third arm in contact with said stop, means for actuating said third arm whereby to impart normal operative movement to said guide, and means under control of the operator for independently actuating said second arm to impart an abnormal movement to said guide and thereby to bring said cutter into severing relation with the thread carried by the needle.

14. A shoe sewing machine having, in combination, a needle, a looper and operating mechanism therefor, a member normally operative to tension the thread between the supply and the looper, means for severing the thread constituting the needle loop, and devices for simultaneously actuating said severing means and for rendering said tension member inoperative.

15. A chain stitch shoe sewing machine having, in combination, a hook needle and a looper, a main shaft from which said needle and looper are operated in the formation of stitches, means for stopping said shaft during a forward rotation thereof with the needle in retracted position, an auxiliary take-up device normally acting to tension the thread between the looper and the supply, a thread-cutter and devices for actuating the cutter to sever the thread and for rendering said auxiliary take-up ineffective simultaneously with such stopping of the shaft.

16. In a shoe sewing machine, in combination, stitch forming and thread controlling instrumentalities including an auxiliary take-up, a spring for actuating said take-up, means for operating said instrumentalities for the formation of stitches, a thread-cutter, and mechanism for stopping the operation of said instrumentalities and for simultaneously actuating the cutter to sever the thread and for rendering said take-up spring ineffective.

17. A chain stitch shoe sewing machine having, in combination, a needle, a looper, a thread-cutter, and a spring actuated pivoted take-up, a main shaft from which said needle and looper are operated, mechanism to arrest the forward rotation of said shaft with the needle in a predetermined position, said mechanism comprising an oscillatable member, and a device actuatable by said member substantially simultaneously with the stopping of said shaft for actuating the cutter to sever the thread and for swinging said take-up upon its pivot in opposition to its actuating spring.

18. A shoe sewing machine having, in combination, a hooked needle and a looper, a main shaft from which said needle and looper are operated, a pivotally mounted auxiliary take-up, a spring for swinging said take-up rearwardly to tension the thread, a thread-cutter, stop mechanism for

- arresting the forward rotation of said shaft, said stop mechanism comprising a rock shaft having an arm fast thereon, an operative connection between said rock-shaft and a thread-cutter for actuating the latter and a link having one end thereof pivotally connected to said arm and the opposite end thereof guided for movement into contact with an element of said take-up, whereby upon stopping of the main shaft and rocking of said rock shaft the auxiliary take up is swung upon its pivot into inoperative position in opposition to its actuating spring.
5. 19. In a chain stitch shoe sewing machine having, in combination, a needle and a looper, a main shaft from which said needle and looper are operated, a pivoted needle guide, a thread cutter mounted thereon, a spring actuated auxiliary take-up, and stop
- mechanism for stopping the forward rotation of the main shaft in a predetermined position such mechanism comprising devices for simultaneously actuating the needle guide to cut the thread of the last needle loop and for rendering said take-up ineffective.
20. The combination in a chain-stitch wax-thread shoe sewing machine having stitch forming devices including a hooked needle and a looper, of means for actuating said devices for the formation of stiches, mechanism for stopping said devices in a predetermined position, and means for automatically severing the thread at a point adjacent the work.
10. 20. The combination in a chain-stitch wax-thread shoe sewing machine having stitch forming devices including a hooked needle and a looper, of means for actuating said devices for the formation of stiches, mechanism for stopping said devices in a predetermined position, and means for automatically severing the thread at a point adjacent the work.
15. 25. In testimony whereof, I have signed my name to this specification.
30. 35. FÉLIX EMILE VALOIS.
